UNITED STATES PATENT OFFICE

141,476

DESIGN FOR A SEAL OR SIMILAR ARTICLE

Milton A. Tomlinson, Cleveland, Tenn.

Application March 10, 1945, Serial No. 118,400

Term of patent 14 years

(Cl. D59—2)

To all whom it may concern:

Be it known that I, Milton A. Tomlinson, a citizen of the United States, residing at Cleveland, in the county of Bradley and State of Tennessee, have invented a new, original, and ornamental Design for a Seal or Similar Article, of which the following is a specification, reference being had to the accompanying drawing, forming part thereof.

Figure 1 is a plan view of a seal, or similar article, showing my new design, and

Figure 2 is an edge elevational view thereof.

I claim:

The ornamental design for a seal or similar article, as shown.

MILTON A. TOMLINSON.
